UNITED STATES PATENT OFFICE.

HENRY C. PAPEMAIER, OF NORTH TROY, NEW YORK.

CLAMP FOR LAMP GUARDS AND SHADES.

1,333,569.

Specification of Letters Patent.

Patented Mar. 9, 1920.

Application filed August 4, 1919. Serial No. 315,262.

To all whom it may concern:

Be it known that I, HENRY C. PAPEMAIER, a citizen of the United States, residing at North Troy, in the county of Rensselaer and State of New York, have invented new and useful Improvements in Clamps for Lamp Guards and Shades, of which the following is a specification.

This invention relates to a combined lamp shade and guard.

The primary object of the invention is to provide means whereby a lamp shade and guard may be applied to an incandescent lamp and locked thereon for the purpose of protecting the lamp from being broken or stolen and from preventing the unauthorized removal of either the shade or guard.

Another object of the invention is to provide a novel form of interlocking engagement between the guard and shade, the latter being locked upon the lamp and engaged with the guard in such manner as to render the removal of the latter, or the removal or breakage of the lamp impossible, without first removing the shade. For the accomplishment of this object, the invention includes the provision of a novel form of lamp guard adapted to be placed upon a lamp socket and held thereon by removable sectional spacing and clamping plates, the latter being held in engagement with the guard and shade by the locking ring.

The invention further consists in the following novel combination and arrangement of parts, to be hereinafter more fully described and illustrated in the accompanying drawings.

In the drawings:

Figure 1 illustrates the application of the invention to an incandescent lamp, the lamp shade and locking means being shown in section.

Fig. 2 is a fragmentary plan partly broken away to show the locking ring securing means.

Fig. 3 is an enlarged horizontal section showing the means for locking the shade and guard to the lamp.

Fig. 4 is a detail elevation of the guard removed from the lamp.

Fig. 5 is a detail perspective of the semi-circular clamping plates shown in separated relation.

Fig. 6 is a bottom plan of the guard.

Fig. 7 is a detail plan of the locking pin.

Referring to the drawings in detail, wherein like characters of reference denote corresponding parts, the reference character 10 indicates a lamp socket, which is provided with the usual restricted shade engaging neck 11. The lamp guard is preferably formed of wire, as indicated at 12 and includes a plurality of sections, preferably three in number, which are formed of spaced wire 13, having one end secured to a ring 14 and the opposite ends secured to an attaching sleeve, which is formed of a plurality of sections 15. These sections are formed with an inwardly extending rib 16, which, when the sections are secured upon the socket 10 in the form of a ring engage the neck 11. The guard is further provided with a spacing ring 17, through which each of the wires 13 pass, the said ring serving to hold the wire in proper position.

The shade, which is shown at 18, may be of any desired shape or form, the one shown serving merely to show the application of the invention. This shade carries at its small end, that is the end which engages the socket 10, a clamping ring 19, the latter engaging both the shade which is formed with a bead 20 and the ring 14. The clamping ring 19 is formed with inner and outer peripheral flanges 21 and 22, which are cross sectionally curved, the inner flange being of a greater depth than the outer flange, so as to engage within the groove formed by the rib 16 of the ring 14, while the outer flange 22 provides a groove for the reception of the bead 20 of the shade 18. The clamping ring 19 is formed of a plurality of sections, preferably two in number, so as to permit of its being positioned upon and removed from the shade and guard.

The clamping ring 19 is held in engagement with the shade and guard by means of a locking ring 23, the latter being of split formation and provided with offset ears 24, which are perforated for the reception of a screw or bolt 25. The screw or bolt 25 receives upon one end a flanged sleeve 26, which is positioned over a nut 27, the latter being adapted to be engaged by a suitable socketed key for positioning and removing the nut.

In positioning the parts, the shade is first placed upon the socket and the guard expanded and slipped over the end of the lamp with the ring 14 within the opening of the

shade. The clamping ring 19 is then adjusted with its flanges in engagement with the guard and shade and the locking ring is positioned around the flange 22 of the 5 ring 19 and secured thereon by means of the screw or bolt 25, which serves to securely hold the parts in position.

The invention is susceptible of various 10 changes in its form, proportions and minor details of construction and the right is herein reserved to make such changes as properly fall within the scope of the appended 15 claims.

Having described the invention, what is 15 claimed is:

1. A device of the class described comprising a lamp guard, means carried by the lamp guard for engagement with a lamp socket, a lamp shade, interengaging means 20 between said guard and shade, sectional clamping plates engaging said guard and shade and means for preventing the separation of the plate sections.

2. A device of the class described comprising a lamp guard, means carried by the lamp guard for engagement with a lamp socket, a lamp shade, interengaging means 25 between said guard and shade, sectional clamping plates, inner and outer peripheral flanges carried by said plates for engagement with said guard and shade and means

for preventing the separation of the plate sections.

3. A device of the class described comprising a lamp guard, means carried by the 35 lamp guard for engagement with a lamp socket, a lamp shade, interengaging means between said guard and shade, sectional clamping plates, inner and outer peripheral transversely curved flanges engaging said 40 guard and shade and means for preventing the separation of the plate sections.

4. A device of the class described comprising a lamp guard, means carried by the lamp guard for engagement with a lamp 45 socket, a lamp shade, interengaging means between said guard and shade, sectional clamping plates engaging the guard and shade and having an outer peripheral bead and a transversely curved split locking ring 50 removably secured upon said bead for preventing the separation of the plate sections.

5. A device of the class described comprising a lamp guard, means carried by the 55 guard for engagement with a lamp socket, a lamp shade, interengaging means between said guard and shade, sectional clamping plates engaging said guard and shade and a transversely grooved split locking ring removably secured to the plates.

In testimony whereof I affix my signature.
HENRY C. PAPEMAIER.
